Primary Examiner — Elizabeth J Oswecki(74) *Attorney, Agent, or Firm* — Gary L. Eastman, Esq.(57) **CLAIM**

The ornamental design for a zipper shoe, as shown and described.

DESCRIPTION

FIG. 1 is a top front perspective view of a zipper shoe showing my new design;

FIG. 2 is a bottom back perspective view thereof;

FIG. 3 is an exploded front perspective view thereof shown in a detached configuration;

FIG. 4 is a right side view thereof;

FIG. 5 is a left side view thereof;

FIG. 6 is a front view thereof;

FIG. 7 is a back view thereof;

FIG. 8 is a top view thereof; and,

FIG. 9 is a bottom view thereof.

The broken lines shown on the zipper shoe represent thread stitching.
